HEIM, GERMANY.

THROTTLE-VALVE FOR CARBURETERS.

1,162,576.

Specification of Letters Patent. Patented Nov. 30, 1915.

Application filed January 14, 1915. Serial No. 2,292.

To all whom it may concern:

Be it known that we, PAUL DAIMLER, a subject of the King of Wurttemberg, residing at Cannstatt, Wurttemberg, Germany, and RUDOLF SLABY, a subject of the King of Prussia, residing at Stuttgart, Wurttemberg, Germany, have invented certain new and useful Improvements in Throttle-Valves for Carbureters, of which the following is a specification.

Our invention relates to a throttle valve for carbureters of internal combustion motors.

It has for its object to provide a carbureter of greater efficiency than those at present in use.

As is well known, the composition of the mixture of gasoline or petrol and air introduced into the cylinders of combustion motors should be the same at all times, no matter what speed the motor is running at. Now, in the carbureters of the sprayer type the admission of petrol is dependent upon the suction power of the motor. When the speed is increased, by altering the section of the admission duct to the mixing chamber the suction power at the main air nozzle of the carbureter is increased also, and more air is drawn into the carbureter than before. However, the petrol will not be able from the beginning to flow through its nozzle with an equally increased speed, and in consequence thereof, whenever the section of said duct is increased, an excess of air will at first be drawn into the motor and the carbureter will require some time to reestablish the proper proportions of fluid fuel and air in the mixture, the petrol being much slower than air with regard to acceleration of flow.

Therefore the supplementary air valves, which are usually opened together with the suction valve, must be arranged in such a manner as to allow the motor during acceleration to draw in a quantity of air just sufficient to prevent it from stopping. Such a quantity of air, however, does not suffice, especially when the carbureter is only half open, for a satisfactory mixture at constant speed, as soon as the speed of inflow of the petrol has been increased in accordance with the increase in speed of the air, and therefor the carbureter will in such a case receive too little air and too much petrol. According to our invention these drawbacks are avoided by providing the throttle valve

controlling the section of the admission passage to the mixing chamber with a supplementary air valve, the connection between the two valves being an elastic one, so that, whenever the section of said passage is suddenly increased, the supplementary air admission openings will at first be closed more or less by the supplementary air valve. Therefore while the amount of mixture drawn into the mixing chamber is increased, as well as the amount of air drawn through the primary air inlet, the amount of air admitted through the auxiliary air inlet is reduced. Later on the supplementary air valve will, under the action of a spring or the like, automatically reopen the said openings, the position of the throttle valve not being influenced thereby.

The drawings annexed to this specification show the preferred form of a carbureter according to our invention.

b is the throttle valve, *a* is a rod controlling said valve, and *c* is a cylinder arranged within the valve and communicating with the outer air through a narrow bore *d* in rod *a*. A cylinder *f* surrounding rod *a* is arranged piston-like within the cylinder *c*; the supplementary air valve *g* fastened to cylinder *f* is held by a spring *h* in the position shown in the drawing, the supplementary air admission openings *i* being open. One end of the spring *h* abuts against a plate *m* integral with the casing in which the throttle moves. The whole throttle mechanism is surrounded by a jacket *n* provided with a suitable inlet, not shown, for the main air supply.

Whenever, in order to run the motor at an increased speed, the throttle valve *b* is displaced in the direction of the arrow, the air within the cylinder *c* is compressed, but owing to the reduced section of bore *d* it cannot escape freely and therefore the piston *f* is displaced also. At the same time the supplementary air valve *g* compressing spring *h* is displaced toward the left and the openings *i* are closed. In consequence thereof, whenever an acceleration of the motor is effected, nothing but main air is admitted at first into the mixing chamber *k*, thereby producing an acceleration of the flow of petrol through the nozzle. After the cylinder *c* has come to rest, the compressed spring *h* in acting upon the supplementary air valve *g* will cause the air within

the cylinder *c* to be expelled through the bore *d*. The supplementary air valve *g* will then return to its initial position and the openings *i* will reopen and admit supplementary air.

We claim:

1. In a carbureter of the sprayer type for internal combustion motors, in combination, a throttle valve, a supplementary air valve, means controlled by the throttle valve and connected with said supplementary air valve for temporarily stopping the admission of supplementary air, and means for automatically restarting the admission of supplementary air.
2. In a carbureter of the sprayer type for internal combustion motors, in combination, a throttle valve, a cylinder closed at one end within said valve, a piston adapted to reciprocate within said cylinder, a supplementary air valve connected with said piston and a spring adapted to drive said piston into said cylinder and to open the supplementary air valve.
3. In a carbureter of the sprayer type for internal combustion motors, in combination, a throttle valve, a cylinder closed at one end within said valve, a valve stem surrounded by said cylinder, a narrow bore within said stem adapted to form a connection between the interior of the cylinder and the outer air, a piston surrounding said valve stem adapted to reciprocate within said cylinder, a supplementary air valve connected with said piston and a spring adapted to drive said piston into said cylinder and to open the supplementary air valve.
4. The combination with a carbureter of

the sprayer type having primary and auxiliary air inlets and a throttle valve controlling the area of the mixture passage thereof, of means whereby the area of the auxiliary air inlet will be temporarily reduced automatically when the throttle valve is suddenly adjusted to increase the area of the mixture passage, for the purpose described.

5. The combination with a carbureter of the sprayer type having primary and auxiliary air inlets and a throttle valve controlling the area of the mixture passage thereof, of means for automatically closing the auxiliary air inlet when the throttle valve is suddenly adjusted to increase the area of the mixture passage, said auxiliary air inlet being again opened automatically independent of any movement of the throttle valve, for the purpose described.

6. The combination with a carbureter of the sprayer type having primary and auxiliary air inlets and a throttle valve controlling the area of the mixture passage thereof, of a valve for the auxiliary air inlet, and means whereby when the throttle valve is suddenly opened the valve for the auxiliary air inlet will be automatically adjusted to reduce the area of said air inlet, said air valve being automatically opened independent of any change in the position of the throttle valve, for the purpose described.

In witness whereof we have hereunto set our hands in the presence of two witnesses.

PAUL DAIMLER.
RUDOLF SLABY.
